UNITED STATES PATENT OFFICE.

PETER SHARP HYSLOP, OF WALMER, ENGLAND.

HEAT-EXCHANGER FOR FLUIDS.

SPECIFICATION forming part of Letters Patent No. 609,676, dated August 23, 1898.

Application filed December 28, 1897. Serial No. 664,075. (No model.)

To all whom it may concern:

Be it known that I, PETER SHARP HYSLOP, a subject of the Queen of Great Britain and Ireland, and a resident of Walmer, in the county of Kent, England, have invented an Improved Heat-Exchanger for Fluids, of which the following is a specification.

My said invention has for its object to increase the efficiency of heat-exchanging apparatus for fluids.

My improved apparatus has been more especially designed for use in conjunction with a system of treating sewage by high heat to disinfect and sterilize it, the purpose being to economize in fuel by regenerating or recovering the heat by transferring it from the outgoing heated liquid to the incoming cold liquid. My heat-exchanging apparatus may, however, be used for many other purposes.

It consists, essentially, of a vessel in which separate passages are formed for the ingoing cold fluid to be heated and for the fluid from which the heat is to be obtained by means of a specially-constructed partition made of a thin metal sheet arranged in a zigzag or serpentine form, the ingoing and outgoing streams of fluids entering the vessel at opposite ends between distributing guide-flanges. The partition may be made with indentations or corrugations to increase the surface and agitate the currents.

My improved apparatus is shown on three accompanying sheets of explanatory drawings, Figures 1 and 2 on Sheet 1 being respectively a longitudinal section and a horizontal section of part of the heat-exchanger. Fig. 3 on Sheet 2 is a transverse vertical section, and Fig. 4 on Sheet 3 is a longitudinal vertical section, of parts of the heat-exchanger as drawn to a larger scale. Fig. 5 is a horizontal section of part of a detail.

My improved heat-exchanger consists of a vessel or casing, a part of which is shown in the drawings, the remainder (which is not shown) being similar. In this casing separate spaces or passages are formed for the ingoing cold fluid to be heated and for the fluid from which the heat is to be obtained.

The heat-exchanger is preferably constructed of cast-iron plates E and is of rectangular form and is preferably supported upon roller-bearings R to permit of a limited longitudi-

nal movement for expansion or contraction, and the part E', separating the ingoing and outgoing streams of fluid, is of thin metal, 55 preferably sheet-copper, which is a good heat-conductor and which is disposed in a zigzag or serpentine form. The zigzag folds are preferably vertical, and the hot fluid enters and leaves the sections by way of the passages 60 P, formed in said sections, passes through the under spaces E², while the cold fluid passes through the upper spaces E³, the two fluids entering at opposite ends of the casing and proceeding in opposite directions. The folded 65 zigzag metal sheet E' is attached to the bottom of the casing in a manner to allow of its expansion and contraction by changes of temperature taking place without straining it. The open ends of the zigzag metal sheet E', 70 communicating with the bottom spaces E², are each closed by being fixed to a piece E³¹, of cut-water section, this piece having a flange E⁴ for fixing it to the casing-bottom plate E, pieces of rubber D⁷, Fig. 4, being interposed between this flange and a rib E⁹ on the casing-bottom plate. The metal sheet E' is made with indentations and projections D⁸, as shown in Fig. 5, or it might be corrugations to cause agitation of the fluids flowing 75 in contact with it. The outside of the casing may be covered or coated with non-conducting material E⁵, such as felt or silicate cotton, to prevent loss of heat by radiation, and it is further covered with quilted felt or canvas or 80 other suitable material to prevent loss of heat by convection.

Provision is made for quickly cleaning the interior of the heat-exchanger, overhead traveling lifting apparatus E⁶ being arranged for 90 raising the covers of the casings, and rotatory or other suitable brushing apparatus is provided for operating on the metal sheet or other parts.

The inlets and outlets for the fluids are of 95 a bottle-neck form and have within them guide-flanges E⁷ to distribute the ingoing fluid and collect the outgoing fluid in a uniform manner to and from all the passages in the casing.

The heat-exchanger communicates with any desired apparatus by pipes E⁸, fitted with stuffing-box joints to allow of expansion and contraction.

What I claim as my invention is—

1. A heat-exchanger for fluids, comprising a vessel in which separate passages are formed, for the ingoing cold fluid to be heated, and for the fluid from which the heat is to be obtained, by a partition made of a thin metal sheet in a zigzag or serpentine form, with distributing guide-flanges leading to the passages formed by the zigzags, substantially as herein set forth.
2. A heat-exchanger for fluids, comprising a vessel with inlets and outlets and a separating-partition of thin metal of zigzag section,

to form passages for the flow of the fluids, the said zigzag partition having also indentations or projections, to cause agitation of the flowing fluids, as and for the purpose described.

In testimony whereof I have signed my name to this specification in the presence of 15 two subscribing witnesses.

PETER SHARP HYSLOP.
